THROTTLE VALVE MECHANISM FOR FLUID
ACTUATED ROTARY TOOLSEdgar R. Whitledge, Mantua, Ohio, assignor, by
mesne assignments, to Reed Roller Bit Com-
pany, Houston, Tex., a corporation of Texas

Application January 30, 1946, Serial No. 644,372

7 Claims. (Cl. 192—.084)

1

This invention relates to improvements in rotary power tools, such as screw drivers, nut runners, and the like. More particularly the invention has to do with automatic means for operating the throttle valve of a fluid motor by which the tool is driven in a manner such that when the tool is pressed against the work the power comes on automatically.

One of the objects of the invention is the provision of a power tool with automatic control means.

Another object is the provision in such a tool of automatic control means which may be readily removed, after which the tool may be controlled manually in the usual manner.

Another object is the provision in a tool of the character described of clutch elements spring biased out of engagement, but adapted to engage when the tool is pressed against the work, with means responsive to such clutch engaging movement for automatically opening a throttle valve and supplying pressure fluid to the motor which drives the tool.

Still another object is to provide a tool which combines with such automatic application of power, means for cutting off the power when the torque exerted for turning the work reaches a predetermined level.

Other objects and features of novelty will appear as I proceed with the description of that embodiment of the invention which, for the purposes of the present application, I have illustrated in the accompanying drawings, in which

Fig. 1 is a longitudinal sectional view of a power screw driver embodying the invention, the parts being shown in their idle position with the control valve closed.

Fig. 2 is a similar view with the control valve open and the tool doing work.

Figs. 3 and 4 are perspective views of the driving and driven clutch elements respectively.

Fig. 5 is a front end view of the tool, partly in section, and

Fig. 6 is a fragmental detail view illustrating the interengaging cam faces on clutch elements employed in connection with the invention.

The particular embodiment of the invention herein illustrated comprises a cylindrical casing 10, a backhead 11 and a clutch housing 12, the two latter parts being threadably engaged with the casing 10 at 13 and 14. A fitting 15 designed to be mounted at one end of a flexible compressed air tube, not shown, may be threaded into the backhead 11 as shown. The cavity in which the fitting is mounted is in communication with a

2

short passage 16 leading to a valve chamber 17. A shouldered part of this chamber serves as a seat for a poppet valve 18 which is rigid with a plunger 19 that slides in a bore 20 and extends out beyond the backhead 11 in order to constitute means for opening the valve against the action of a coil spring 21 that abuts against the head of the valve and against a hollowed out screw plug 22 which functions also to close one end of the valve chamber. When the valve is unseated air is admitted into the bore 20 and through a passage not shown into an annular space 23 which is in register with one or more passages 24 in a bearing plate 25, which passages in turn register with one or more passages 26 in a cylinder 27 which fits within the casing 10. From the passages 26 the fluid is directed against blades or vanes 28 of a rotor 29 carried by shaft 30 which has bearing at its upper end in bearing plate 25 and at its lower end in a second bearing plate 31. The exhaust fluid passes into an annular chamber 32 and through one or more ports 33 into another annular chamber 34 under a deflector ring 35 and thence through a slot 36 in the ring out to atmosphere. The fluid motor which has just been described is of conventional construction and the details thereof form no part of the present invention.

On the lower end of shaft 30 there is formed a pinion 37 constituting the sun gear of a planetary reduction gear assembly. This pinion meshes with two or more planet gears 38 that run upon a fixed ring gear 39. Gears 38 have short shafts 40 rotatably mounted in a planet carrier 41 which has bearing in a bushing 42. Carrier 41 has a hollow depending portion which is internally threaded to receive the hollow upstanding shank of a driving clutch element 43, the latter running against a thrust bearing 44. Movement of the carrier in the opposite direction is limited by an out-turned flange 45 on bushing 42. Only sufficient movement of these parts is permitted lengthwise of the tool to afford free running operation. The gearing is designed to provide an appreciable reduction in speed as between the motor and the clutch element 43.

The driving clutch element 43 has a lower surface 46 from which extend downwardly one or more clutch teeth 47. The forwardly moving edges or faces 48 of these teeth are beveled or inclined and are disposed to contact complementary inclined faces 49 on teeth 50 projecting upwardly from a driven clutch element 51. The latter element is provided with a pilot 52 which slides in a bore 53 of element 43, the two ele-

ments being biased toward disengagement by a coil spring 54 which bears at one end against pilot 52 and at the other end against the carrier 41. Hence the clutch elements normally stand in the relation illustrated in Fig. 1 of the drawing.

Shaft 55, preferably formed integral with clutch element 51, carries the tool to be rotated. In the illustrated case the shaft has a screw driver bit formed on its extremity. Shaft 55 has bearing in a sleeve 56 provided at its upper end with a flange 57 that fits slidably in a circular pocket 58 formed in clutch housing 12, and is adapted to seat against a shoulder 59 in the housing. This sleeve is yieldably held in the illustrated position by a coil spring 60 that bears at its upper end against the clutch element 51. Spring 60 is weaker than spring 54, so that normally it is overcome by spring 54 as illustrated in Fig. 1.

Driven clutch element 51 is provided with a peripheral groove 61 in which runs a shoe 62 carried at the lower end of a control member 63 which extends upwardly alongside the housing 12 and casing 10 to a position opposite the rounded extremity of plunger 19. An elongated sheet metal cover or guard 64 of generally channel shape in cross-section is held at its lower end by a foot portion 65 which has an opening therethrough to fit over a lower constricted part of clutch housing 12. At its upper end it is provided with a pair of wings 66 which are perforated to take a pin 67 that extends through them and through a registering hole in the backhead 11. 10 is a block with an inclined or cam surface 73 on its lower side. This block is carried by a screw 71 which is threaded through the upper end of the guard 64 so as to be adjustable up and down between the guard and the backhead 11. The free end of control member 63 is beveled off as shown at 72 at the same angle as the cam surface 73 on the block. In the cam surface 73 there is a step 74 providing a backstop for the outer side of member 63. When the latter member moves upwardly, as viewed in the drawing, surfaces 72 and 73 engage and the member 63 is cammed over until its end snaps into position behind the step 74. This deflection of member 63 exerts pressure on the plunger 19, forcing it transversely of the backhead against the action of spring 21 far enough to unseat valve 18 and provide free flow of pressure fluid to the motor. The provision of step 74 which takes the load of spring 21 eliminates any load upon the rotating clutch element 51, which would otherwise be exerted through the walls of groove 61 and the shoe 62.

Operation.—The idle condition of the tool is illustrated in Fig. 1, where the clutch elements are disengaged and the throttle valve is closed. When the operator applies the bit end of shaft 55 to the work and exerts pressure against the work the driven clutch element 51 is caused to move inwardly of the clutch housing 12 or toward the rear end of the tool, carrying with it the shoe 62 and the control member 63. The beveled surface 72 of the latter meets the inclined face 73 of block 70 below step 74 just before the clutch teeth 47 and 50 are brought into engagement, and upon continued pressure being applied the upper end of the control member is forced inwardly along the face 73, thereby pressing against the plunger 19 and opening the valve. The valve is unseated slightly before the clutch members engage. Hence the motor and the clutch member 43 are turning at a low rate of speed prior to clutch engagement, there-

by insuring smooth clutch action. When the teeth 47 and 50 have come into full engagement the end of control member 63 will move into engagement with the step 74 and will hold the throttle valve in full open position during the continued operation of the tool. It will be seen that with the end of the control member bearing on the step 74 there will be no axial pressure between the shoe 62 and either face of groove 61, the clutch element 51 thus having no drag upon its movement as it is rotated to do the work.

When the work has been completed, as for example when a screw S has been driven tightly into its socket, the resulting resistance to further rotation will be transmitted to the clutch teeth 50 and 47 and the inclined surface 48 of tooth 47 working against the inclined surface 49 of tooth 50 will cam the clutch element 51 downward or outward relatively. Simultaneously, shoe 62 will move relatively downward and will pull the upper end of control member 63 off the step 74, permitting spring 21 to seat throttle valve 18 and cut off the flow of pressure fluid to the motor. The tool will then cease to operate, and as soon as the operator withdraws it from the work spring 54 will further separate the clutch elements, causing the parts to again resume their positions of Fig. 1.

Having thus described my invention, I claim:

1. In a power tool, a rotary fluid motor, a driving clutch element operatively connected with said motor, a driven clutch element, a throttle valve transversely arranged at the rear end of the tool and comprising a plunger, actuating means for said valve comprising a longitudinally movable member coupled with said driven element and extending across the extremity of said plunger, and means responsive to the longitudinal movement of said member for camming it inward to move said plunger and open said valve as the clutch elements come into engagement.

2. A power tool as claimed in claim 1, in combination with a longitudinally extending removable sheet metal cover forming an enclosure for said longitudinally movable member and carrying said camming means.

3. In a power tool, a rotary fluid motor, a driving clutch element operatively connected with said motor, a driven clutch element, a throttle valve transversely arranged at the rear end of the tool and comprising a plunger, spring means for pressing said plunger outward and closing said valve, actuating means for opening said valve comprising a longitudinally movable member coupled at one end with said driven element and extending across the extremity of said plunger, a cam for engaging the other end of said control member and camming the same inwardly to move said plunger and open said valve as the clutch elements come into engagement, said cam having a step therein acting as a backstop for said control member to take the load impressed by said spring pressed plunger in its valve open position.

4. In a power tool, a rotary fluid motor, planetary reduction gearing symmetrically disposed about the axis of said motor on the forward side thereof, a driving clutch element operatively connected with the output end of said reduction gearing, a driven clutch element, said elements being adapted to engage each other as one of them is shifted relatively toward the other, a throttle valve at the rear end of the tool, and actuating means therefor coupled with said driven clutch element extending alongside said motor

and reduction gearing for opening the throttle valve as the clutch elements engage.

5. In a power tool, a rotary fluid motor, a driving clutch element operatively connected with said motor, a driven clutch element, said elements being adapted to engage each other as one of them is shifted relatively toward the other, a throttle valve, said driven element having a peripheral groove therein, and actuating means for opening said valve when said driven clutch element comes into engagement with said driving element, said means comprising a longitudinally extending member having a shoe running in said groove.

6. In a fluid actuated rotary tool, a motor, a work engaging member rotatable by said motor, a driving and a driven clutch element between said motor and member one movable relative to the other in one direction for transmitting rotation to said member and in the other direction for preventing transmission of rotation to said member, a throttle valve, spring means normally maintaining said throttle valve in a closed position, and means operatively associated with said throttle valve responsive to the movement of one of said elements in one direction for opening said throttle valve and in the other direction for enabling said throttle valve to be closed by said spring means.

7. In a fluid actuated rotary tool, a motor, a work engaging member rotatable by said motor, a driving and a driven clutch element between said motor and member one movable relative to the other in one direction for transmitting rotation to said member and in the other direction for preventing transmission of rotation to said member, a throttle valve, spring means normally maintaining said throttle valve in a closed position, a throttle valve actuating member coupled with one of said clutch elements for movement therewith relative to the other, and cam means responsive to the movement of said throttle valve actuating member in one direction for causing it to press said throttle valve into open position.
